UNITED STATES PATENT OFFICE.

ERNEST M. FRECK AND FRANK V. ROBERTS, OF ASHEVILLE, NORTH CAROLINA.

WICK-CLEANING ATTACHMENT FOR LIQUID-FUEL BURNERS.

1,287,664.

Specification of Letters Patent. Patented Dec. 17, 1918.

Application filed March 22, 1918. Serial No. 234,000.

To all whom it may concern:

Be it known that we, ERNEST M. FRECK and FRANK V. ROBERTS, citizens of the United States, residing at Asheville, in the county of Buncombe and State of North Carolina, have invented certain new and useful Improvements in Wick-Cleaning Attachments for Liquid-Fuel Burners, of which the following is a specification.

This invention relates to wick cleaning appliances for liquid fuel burners and has as its primary object to provide a wick cleaning device which will permit of the wicks of a blue flame oil stove or liquid fuel burners of other types being readily cleaned without the necessity of removing any of the burner parts and wiping off the edge of the wick as is at present necessary and which operation not only requires time but also results in soiling of one's hands. While the device embodying the present invention is designed more particularly as an attachment for the burners of blue flame oil stoves which are now in use and is adapted for application to practically any of the ordinary types of such burners, it will be understood, of course, that the principles of the invention may find embodiment directly in the initial construction of such burners.

The present invention also has as its object to provide a device for the purpose stated the presence of which in the burner structure will not in any way interfere with removal of the flame spreader or any other of the detachable parts of the burner, the cleaning member of the device being in fact removable with the flame spreader whereby to permit of ready cleaning of these parts.

Another object of the invention is to so locate the actuating member for the device that the same may be conveniently manipulated without likelihood of soiling or burning one's fingers.

In the accompanying drawings:

Figure 1 is a view in front elevation of one end of a blue flame oil stove the burners of which are equipped with the device embodying the present invention;

Fig. 2 is a vertical longitudinal sectional view through the device applied;

Fig. 3 is a bottom plan view of the structure shown in Fig. 2;

Fig. 4 is a group perspective view illustrating the cleaning member of the device and the actuating member therefor;

Fig. 5 is a fragmentary sectional view illustrating the character of the cleaning surface of the said cleaning member;

Fig. 6 is a horizontal sectional view on the line 6—6 of Fig. 2 looking in a downward direction;

Fig. 7 is a vertical sectional view taken substantially on the line 7—7 of Fig. 8;

Fig. 8 is a similar view taken substantially on the line 8—8 of Fig. 3.

In the drawings the numeral 1 indicates a liquid fuel supply pipe, which pipe leads from the usual reservoir 2 and supports the burner. The burner is shown in detail in Fig. 2 of the drawings, and the same comprises the usual wick tube 3 having the inner and outer walls indicated respectively by the numerals 4 and 5. The wick is indicated by the numeral 6 and is supported by the usual carrier 7 for vertical adjustment with in the wick tube. Secured to the inner wall of the wick tube 4 is a bracket 8 which extends below the lower end of the said tube and has a portion 9 extending laterally and terminating in a hooked member 10 formed to engage and partly surround the under side of the liquid fuel supply pipe 1, the lower end of the portion 8 of the said bracket member being designed to engage the upper side of the said pipe both as clearly shown in Figs. 2 and 8 of the drawings. As is usual, the liquid fuel supply pipe 1 is provided with an outlet in its upper side indicated by the numeral 11 and the wick tube 3 is provided at a point diametrically opposite the bracket member 8 with a nipple 12 having a passageway 13 communicating with the outlet 11 from the liquid fuel supply pipe. The nipple 12 has a down-turned end or branch 14 which is designed to seat in a liquid tight manner against a suitable boss 15 formed upon the upper side of the pipe 1 and surrounding the outlet 11, and the said nipple is clamped to the pipe in a manner which will now be explained. A yoke 16 comprising spaced side members 17 and a connecting member 18, is disposed to straddle the nipple 12 and the said pipe 1 and the lower ends of the side members 17 are provided with hook portions 19 with which is engaged a link 20 designed to prevent spreading of these ends. A clamping screw 21 is fitted through an opening 22 formed in the connecting member 18 of the yoke 16 and is adjustably threaded through

100
105
110

a nut 23 which is confined between the side members 17 of the said yoke and, therefore, held against turning movement, the lower end of the screw 21 seating in a suitable depression 24 formed in the upper side of the nipple 12. Of course, by tightening the screw 21, the branch 14 of the nipple will be firmly bound to the boss 15 so as to form a liquid-tight connection between these parts.

10 As is usual, the flame spreader, indicated by the numeral 25, is fixedly mounted in the upper end of the draft tube of the burner indicated by the numeral 26, the said draft tube being provided at its upper end 15 with vertically extended spaced portions 27 having tongues 28 fitted through openings in the spreader 25 and bent down to secure the spreader in place. The attachment embodying the present invention includes a cleaning member which is clearly illustrated in Figs. 2 and 4 of the drawings, and this member which is indicated in general by the numeral 29, includes an annular head 30 provided at its inner periphery with a depending annular flange 31 which fits rotatably about the exterior of the upper end of the draft tube 26, the said head 30 being located between the upper end of the wick tube and the under side of the flame spreader 25. A suitable spider 32 has the ends of its arms connected to the head 30, the said arms of the spider extending between the spaced extended portions 27 of the draft tube 26 and the said portions 27 constituting, by reason of the engagement of the arms of the spider thereagainst, stops to limit the rotation of the head 30 in the operation of the device. Also the arms of the spider 32, resting upon the upper edge of the draft tube 26, serve as a means for preventing downward displacement of the head 30 with relation to the flame spreader 25 and the draft tube 26. The under side of the head 30 at the outer peripheral portion thereof 35 constitutes the wick cleaning surface and this portion of the under side of the head is provided with an inwardly extending horizontal flange 32' the under side of which is serrated as indicated by the numeral 33, the serrations being more or less well defined as found desirable. The numeral 34 indicates an actuating stem for the cleaning member 29, this stem being secured at its upper end in any suitable manner to the central portion of the spider 32 and being designed to extend downwardly axially within the draft tube 26 and having its lower end of polygonal formation, as indicated by the numeral 35.

50 The lower end of the stem or spindle 34 above described is designed to coat with the actuating means of the device, which actuating means will now be described. The numeral 36 indicates a circular disk which is secured in any suitable manner to the connecting portion 37 of a yoke clip, the side members of which clip are indicated by the numeral 38, and this clip is designed to be disposed upon the pipe with its side members straddling said pipe and a suitable 70 clamping bolt 39 fitted through slots 40 formed in the said side members of the clip and is to be tightened for the purpose of securing the clip to the pipe with the disk 36 horizontally disposed and with its central portion in axial alignment with the spindle 34. The disk 36 constitutes a support for a rotatable socket member comprising a base 41 which is rotatably disposed at its peripheral portion upon the upper face of the disk 80 and is held thereto by means of suitable lugs 42 which are struck down from the periphery of the base 41 and engage beneath the periphery of the disk 36. The socket member comprises further a throat portion 85 43 which extends upwardly from the central portion of the base 41 and is interiorly flared, as indicated by the numeral 44, so that when the flame spreader 25, cleaning member 29, and draft tube 26 are fitted into place, the lower end 35 of the spindle 34 will be guided by the walls of the throat 43 to provide for engagement of the polygonal end 35 of the said spindle in a similarly formed opening 45 located axially in the base 41 at the lower end of the throat 43. A lever member 46 extends outwardly and downwardly from the periphery of the base 41 and to a suitable distance beyond the base of the burner as a whole where it may 90 be readily grasped, without likelihood of burning one's fingers or soiling them, for the purpose of rotating the base 41. In the use of the device, assuming that the wick 6 has been raised by the wick raising and lowering means ordinarily provided, until the upper edge of the wick is in more or less firm contact with the serrated surface 33 of the head 30 of the cleaning device, the lever member 46 is moved backwardly 100 and forwardly several times so as to impart rotary motion to the base 41 and, consequently, to the head 30 of the cleaning device so that the serrated surface 33 will be caused to move over the said upper edge 110 of the wick and break off and dislodge any charred portions or soot which has accumulated thereon.

Having thus described the invention, what is claimed as new is:

111. In a device of the class described, the combination with a liquid fuel burner and a fuel supply pipe therefor, the burner having a wick tube, of a wick cleaning member including a head rotatably mounted at the 125 upper end of the tube and having a wick rubbing surface positioned above the upper end of the tube, a rotatable member mounted upon the fuel supply pipe, a stem extending downwardly from the cleaner head and hav-

130

ing detachable engagement with the said rotatable member, and means whereby the member may be rotated.

2. In a device of the class described, the combination with a liquid fuel burner and a fuel supply pipe therefor, the burner having a wick tube, of a wick cleaning member including a head rotatably mounted at the upper end of the tube and having a wick rubbing surface positioned above the upper end of the tube, a rotatable member mounted upon the fuel supply pipe, a stem extending downwardly from the cleaner head and having detachable engagement with the said rotatable member, means whereby the member may be rotated, and a lever member extending from the rotatable member to a point exteriorly of the base portion of the burner.

3. In a device of the class described, the combination with a liquid fuel burner having a wick tube, of a wick cleaning member rotatably mounted at the upper end of the tube and having a wick rubbing surface, a member rotatably mounted and having a

polygonal socket, a stem extending downwardly from the cleaning member axially thereof and provided with a polygonal lower end removably fitting in the socket, and a finger piece extending from the rotatable member.

4. In a device of the class described, the combination with a liquid fuel burner having a wick tube and a flame spreader, of a wick cleaning member rotatably mounted beneath the flame spreader and having a wick rubbing surface, a member rotatably mounted within the lower end of the wick tube and provided with a polygonal socket, a stem connected with the wick cleaning member and extending downwardly axially therefrom and having a polygonal lower end fitting removably in the socket, and a finger piece extending from the last mentioned member.

In testimony whereof we affix our signatures.

ERNEST M. FRECK. [L. S.]
FRANK V. ROBERTS. [L. S.]
